[57] CLAIM

The ornamental design for electric plug with circuit breaker, as shown and described.

DESCRIPTION

FIG. 1 is a top, front, left side perspective view of a combined electric plug and circuit breaker showing our new design;

FIG. 2 is a rear elevational view thereof;

FIG. 3 is a front elevational view thereof;

FIG. 4 is a right side elevational view thereof;

FIG. 5 is a left side elevational view thereof;

FIG. 6 is a top plan view thereof;

FIG. 7 is a bottom plan view;

FIG. 8 is a front elevational view of a second embodiment of our new design;

FIG. 9 is a right side elevational view of the embodiment illustrated in FIG. 8;

FIG. 10 is a front elevational view of a third embodiment of our new design; and

FIG. 11 is a right side elevational view of the embodiment illustrated in FIG. 10.

The top and bottom views of the second and third embodiments differ from those of the first only in the arrangement of the connector prongs.
